UNITED STATES PATENT OFFICE.

HARRY A. DOUGLAS, OF BRONSON, MICHIGAN.

LAMP.

1,358,065.

Specification of Letters Patent.

Patented Nov. 9, 1920.

Application filed February 4, 1918. Serial No. 215,332.

To all whom it may concern:

Be it known that I, HARRY A. DOUGLAS, citizen of the United States, residing at Bronson, in the county of Branch and State 5 of Michigan, have invented a certain new and useful Improvement in Lamps, of which the following is a full, clear, concise, and exact description.

My invention relates to lamps of the class 10 commonly known as headlights, though the lamp of my invention is not to be limited to any particular use to which it may be put. My invention relates particularly to those lamps in this class that employ concave reflectors that are mounted to turn or tilt with 15 respect to the casings that house the reflectors in order that the direction of the light may be varied without adjusting the position of the casings. Such reflectors, when employed, 20 in lamps that are upon automobiles, are usually mounted to swing upon horizontal axes in order that the light may fall upon parts of the roadway at differing distances from the automobiles. I provide direct 25 turning engagement of the reflectors with their casings in order that the reflectors may be tilted.

The means for turning a reflector with respect to its casing is, in accordance with another feature of my invention, an electro-magnetic mechanism which is disposed within the casing and the space which is provided between the casing and the reflector. This electro-magnetic mechanism also enables me to eliminate the slot in the casing 35 whether or not the reflector has direct turning engagement with the casing.

I will explain my invention more fully by reference to the accompanying drawing 40 showing the preferred embodiment thereof and in which Figure 1 is a view in longitudinal section of an electric headlight equipped in accordance with my invention, a diagram of the circuit for controlling the 45 electro-magnetic operating mechanism being also shown in this figure; Fig. 2 is a detail view illustrating preferred means employed for assembling the reflector and its door and for assembling the glass or other light transmitting cover with the front end of the reflector; and Fig. 3 illustrates the pivotal union that is preferably employed between the casing and reflector to supplement the bearing that is afforded by the directly engaging reflector and casing portions.

Like parts are indicated by similar char-

acters of reference throughout the different figures.

The headlight illustrated is an electric headlight employing an incandescent lamp 1 which is coupled with the rear end of a concave reflector 2. This reflector is located mainly within the casing 3 that is normally stationarily positioned upon the lamp bracket or other support. The casing 3 has its front portion 4 in the form of a zone of a sphere. The reflector has a portion 5 which is also a zone of a sphere that is concentric with the zone 4. The reflector portion 5 and the casing portion 4 are in direct engagement forming a joint somewhat in the nature of a ball and socket joint whereby no gap need be introduced between the reflector and casing when the reflector is tilted to an extreme position and whereby no slot need be formed in the casing in order that the reflector may be turned. When the axis of rotation of the reflector is to be substantially fixed with respect to the casing, diametrically aligned pivot points 6 define an axis of rotation for the reflector which is inclusive of the common center of said zone sections 4 and 5. The portion 5 of the reflector is preferably formed by outwardly turning the reflector and directing this outwardly turned portion of the reflector toward the rear. This rearwardly extending portion 5 of the reflector desirably engages the exterior of the casing and where the pivot pins 6 are employed the reflector portion 5 need only be 70 extended sufficiently to the rear to prevent the formation of a gap between the reflector and casing when the reflector is turned to an extreme tilting position. The presence of the pivot pins 6, therefore, enables me to 75 reduce the frictional engagement between the parts 4 and 5 of the lamp, a feature which is advantageous when the reflector is to be tilted by electro-magnetic mechanism, but which is not so important if the reflector is to be tilted by hand. The door 7 of the lamp carries spring clips 8 and 9. The spring clips 8 constitute latches that may be passed through slots 10 (Fig. 2) in the reflector when the door and reflector are 80 85 90 95 100 105 110 assembled. The clips 9 hold the glass cover 11 in front of the reflector. The front margin 7¹ of the door 7 presses the glass cover 11 against the felt ring 12 that engages the front rim of the reflector to guard against entry of dust into the lamp structure.

- The lamp constructed as thus far specifically described in connection with the drawings may have its reflector adjusted with respect to its casing merely by turning the forward part of the reflector by hand, it not being necessary, for such manner of adjustment of the reflector, to have any mechanism within the lamp for turning the reflector.
- Very frequently these lamps are located in places where it is not convenient to adjust the reflectors by hand when it is desired to tilt them. For example, when these lamps are upon automobiles, it is generally not feasible or convenient to engage the reflectors to turn them by hand and in order to avoid the employment of operating mechanism that would make it necessary to slot the casings, I provide electro-magnetic reflector tilting mechanism within the casing that may be controlled by switching mechanism accessible from the chauffeurs' seats. In Figure 1 I have illustrated a solenoid 13 mounted in the space between the rear ends of the reflector and casing. The core 14 of this solenoid has pin and slot connection 15 with one arm of a bell crank 16, this bell crank being pivotally mounted at its elbow upon the bracket 17 also within the casing. The other arm of the bell crank has pin and slot connection 18 with a bracket 19 that is attached to the rear end of the reflector upon the exterior thereof. When the solenoid is energized the reflector is tilted from its normal position. A spring 20 serves to return the reflector to its normal position when the solenoid is deenergized. In order that the presence of the electro-magnetic mechanism within the space between the reflector and casing need not require the formation of a special opening for the passage of the conductor 21 that leads to the solenoid, I pass this conductor through the same electrical coupling 22 through which the conductor 23 passes to the lamp 1. The circuit connections illustrated are of the so-called single pole arrangement, one terminal of the lamp 1 and one terminal of the solenoid 13 being in "grounded" connection with the casing 3, the casing in turn being connected with one terminal of the battery or other source of current 24. A switch 25 is shown between the other terminal of the battery and the conductor 23 while a switch 26 is shown between this same terminal of the battery and the conductor 21. Whenever the reflector is to be tilted the switch 26 is closed to energize the solenoid 13 and when the reflector is to be restored to normal position the switch 26 is opened, the spring 20 then being permitted to restore the reflector to normal position.
- The invention is not limited to all the precise details of construction shown in the drawings, and what I claim is:
1. A lamp including a casing open at its front end, the margin of the casing at said end being contracted and curved inwardly, in the form of a zone of a sphere, a reflector mounted within said casing, the front end of the reflector being curved outwardly and backwardly in the zone of a sphere fitting closely against the outer surface of the front end of the casing, and diametrically opposite pivots between said backwardly curved portion and the casing, the axes of said pivots intersecting the common center of said sphere zones, whereby the surface of said sphere zones are in close contact in all positions of the reflector.
  2. A lamp including a casing the front end of which is curved inwardly in the form of a zone of a sphere having its smallest diameter at the front edge of the casing, a reflector pivotally mounted in said casing, and having an outwardly and backwardly curved flange bent to form the zone of a sphere having its greatest diameter at its rear edge, the surfaces of said sphere zones fitting in sliding contact with each other in all positions of the reflector, and diametrically opposite pivots between said flange and casing, said pivots being located in line with the rear edge of said flange.

In witness whereof, I hereunto subscribe my name this thirtieth day of January A. D., 1918.

HARRY A. DOUGLAS.
